(57) **CLAIM**

I claim the ornamental design for a fishing bait, weight, and hook holder, as shown and described.

DESCRIPTION

FIG. 1 is a top perspective view of a fishing bait, weight, and hook holder showing my new design;

FIG. 2 is a top view of the fishing bait, weight, and hook holder of FIG. 1;

FIG. 3 is a bottom view of the fishing bait, weight, and hook holder of FIG. 1;

FIG. 4 is a side view of the fishing bait, weight, and hook holder of FIG. 1, the opposite side being a mirror image of that shown;

FIG. 5 is a front view of the fishing bait, weight, and hook holder of FIG. 1;

FIG. 6 is a rear view of the fishing bait, weight, and hook holder of FIG. 1; and,

FIG. 7 is a top perspective view of the fishing bait, weight, and hook holder of FIG. 1.

The broken lines are for the purpose of illustrating environment and form no part of the claimed design.

The broken lines illustrate the holder mounted to a portion of a fishing rod and holding a fishing weight attached to a portion of fishing line.
